UNITED STATES PATENT OFFICE.

JEROME R. GEORGE, OF WORCESTER, MASSACHUSETTS, ASSIGNOR TO MORGAN CONSTRUCTION COMPANY, OF WORCESTER, MASSACHUSETTS, A CORPORATION OF MASSACHUSETTS.

ROLLING-MILL.

1,278,136.

Specification of Letters Patent. Patented Sept. 10, 1918.

Application filed November 20, 1914. Serial No. 873,226.

To all whom it may concern:

Be it known that I, JEROME R. GEORGE, a citizen of the United States, residing at Worcester, in the county of Worcester and 5 Commonwealth of Massachusetts, have invented a new and useful Improvement in Rolling-Mills, of which the following is a specification, accompanied by drawings forming a part of the same.

10 My present invention relates to that class of rolling mills employed for the reduction of blooms, and it has for its objects to facilitate the manipulation of the rolled metal; to simplify the construction of the mill; to reduce its cost; and to increase its output. These objects, among others, I accomplish 15 by the construction and arrangement of parts as hereinafter described, the novel features being pointed out in the annexed 20 claims.

Referring to the accompanying drawings,

Figure 1 represents a plan view of the rolling mill embodying my present improvement.

25 Fig. 2 is a front view of a portion of the mill.

Similar reference characters refer to similar parts throughout the different figures.

The rolling mill embodying my present 30 improvement comprises two two-high stands of rolls 1, and 2, with the rolls of each stand having parallel axes and placed adjacent and in staggered relation to each other. The overlapping ends of the rolls in each stand 35 are journaled in an integral housing 3, while the opposite ends of the rolls are journaled in separate housings 4 and 5. The rolls 1 and 2 are driven in opposite directions, preferably by independent motors, not shown, 40 connected with the spindles 6 and 7, while the rolls of each pair are geared together in the usual manner by gearing 8 and 9. The rolls of each stand are provided with a multiplicity of passes designed for the consecutive 45 reduction of a bloom alternately in each stand of rolls. The reduction of the passes is in the same direction in each stand of rolls, for example, the largest pass 10 in the rolls 1 is at the outer end of the rolls, 50 the passes being reduced in size toward the opposite or inner end of the rolls, while the largest pass 11 in the rolls 2 is at the inner end of the rolls, and the passes are reduced in size toward the outer end of the

rolls. By this arrangement of the passes 55 the transverse or sidewise movement of the rolled metal as it passes from one stand of rolls to the other is substantially the same.

On opposite sides of the two stands of rolls are conveyer tables 12 and 13, each comprising a series of positively driven conveyer rolls 14 and 15 receiving their motion from the countershafts 16 and 17, connected with reversible motors, not shown, by which the direction of the rotation of the conveyer 60 rolls may be changed at will. Upon each side of the conveyer tables 12 and 13 are wheels 18, carrying endless belts 19 provided with lugs 20. The sprocket wheels upon one side of the conveyer table 12 are carried 65 upon a countershaft 21, preferably driven by an independent motor, and the sprocket wheels upon one side of the conveyer table 13 are carried upon a countershaft 22, preferably driven by an independent motor. 70

The upper or horizontal portions of the endless chains 19 are carried upon tracks, one of which is shown at 23, Fig. 2, which maintain the horizontal portions of the chain in a plane just below the supporting 75 surfaces of the conveyer rolls 14 and 15, with the lugs 20 projecting above the rolls 14 and 15 far enough to engage a bloom as it is supported upon the rolls 14 and 15, and transfer it thereon by a sidewise movement as the shafts 21 and 22 are rotated. 80 Mounted upon stands 24 between the conveyer rolls are the inclines 25 over which the blooms are moved by the lugs 20. The inclines 25 consist of triangular projections 85 having vertical sides 26. As the bloom reaches the apex or highest point of the incline 25, it falls upon the vertical side 26, causing the bloom to be turned one quarter turn. 90

In operation, the initial rolling is made by the pass 10 in the rolls 1, and is delivered upon the conveyer table 12. The bloom is then moved sidewise across the conveyer table 12 and over the inclines 25, causing it to be turned one quarter turn and brought into alignment with the pass 11 of the rolls 2. The rotation of the rolls in the conveyer tables is then reversed and the bloom carried through the pass 11 and delivered upon 100 the conveyer table 13. The bloom is then transferred sidewise by means of the chains 19 and lugs 20 into alignment with the pass

27 of the rolls 1, and delivered upon the conveyer table 12. The bloom is then transferred in the manner already described, and conducted through the pass 28 of the rolls 5 2. The next sidewise transfer of the bloom brings it into alinement with the pass 29 of the rolls 1. The bloom is then carried consecutively through the passes 30 and 31 to either one of the passes 32 as elected by 10 the operator. After each pass of the bloom through the rolls 1 and 2, the conveyer rolls are rotated to carry the metal into position to be transferred by the belts 19 and lugs 20. The conveyer rolls are then stopped 15 during the transfer and reversed to carry the metal into the next succeeding pass of the rolls 1 and 2.

The reduction of the bloom is effected by the alternate rolling of the metal between 20 the rolls 1 and 2, the bloom being turned one quarter turn after each rolling. The presentation of the bloom to and its delivery from each pair of rolls and its sidewise transfer from one pass to the next succeeding pass is done mechanically and with sufficient rapidity to prevent the undue loss of heat.

I claim,

30 1. A rolling mill comprising two stands of two high rolls placed in staggered relation to each other, with the rolls of each stand provided with a multiplicity of passes for the consecutive reduction of the rolled metal alternately in said stands, with a reduction in the size of the passes from corresponding ends of the rolls in each stand, whereby a uniform lateral movement will

transfer the rolled metal from a pass in one stand of rolls to the next consecutive pass in the other stand of rolls, conveyer tables on 40 opposite sides of said stands of rolls, common to all the passes in said rolls, means for rotating the rolls in said stands in opposite directions, means for transferring the rolled metal by a sidewise movement from its alinement with a pass in one stand of rolls to an alinement with a pass in the other stand of rolls, and a stationary incline having a vertical side interposed in the path of the sidewise movement of the rolled metal, whereby the 50 metal is rotated a predetermined partial revolution during said sidewise movement. 45

2. A rolling mill comprising two stands of two high rolls placed in staggered relation to each other, with the rolls of said 55 stands journaled at one end in independent housings and with the other and adjacent ends of the rolls journaled in a single integral housing.

3. A rolling mill comprising two stands 60 of rolls running in opposite directions, with their passes out of alinement, means for transferring the rolled metal by a sidewise movement from its alinement with a pass in one stand of rolls to an alinement with a 65 pass in the other stand of rolls, and means for rotating the rolled metal about its own axis during said transfer.

Dated this sixteenth day of November, 1914.

JEROME R. GEORGE.
